UNITED STATES PATENT OFFICE.

CHESTER A. FRICK, OF MUNCIE, INDIANA.

DESIGN FOR A BOTTLE REFRIGERATOR.

Application filed May 1, 1925. Serial No. 13,283. Term of patent 14 years.

To all whom it may concern:

Be it known that I, CHESTER A. FRICK, a citizen of the United States, residing at Muncie, in the county of Delaware and State of Indiana, have invented a new, original, and ornamental Design for Bottle Refrigerator, of which the following is a specification, reference being had to the accompanying drawing, forming a part thereof.

In the drawing, the figure is a perspective

view of a bottle refrigerator showing my design.

I claim:

The ornamental design for a bottle refrigerator as shown.

In witness whereof, I CHESTER A. FRICK have hereunto set my hand at Indianapolis, Indiana, this 28th day of April, A. D. one thousand nine hundred and twenty five.

CHESTER A. FRICK.
